H. SMITH.

HEATING STOVE.

No. 17,578.

Patented Aug. 2, 1887.

UNITED STATES PATENT OFFICE.

HOLMES SMITH, OF ST. LOUIS, MISSOURI.

DESIGN FOR A HEATING-STOVE.

SPECIFICATION forming part of Design No. 17,578, dated August 2, 1887.

Application filed June 21, 1887. Serial No. 242,947. Term of patent 14 years.

To all whom it may concern:

Be it known that I, HOLMES SMITH, a British subject, residing in the city of St. Louis, Missouri, have invented and produced a new 5 and original Design for Heating-Stoves, of which the following is a full, clear, and exact description, reference being had to the accompanying photograph, forming part thereof, in which the newly-designed stove is shown in 10 perspective.

The stove under consideration belongs to that class termed "box-stoves," the general characteristic of which is an oblong rectangular body having a hearth at one of its ends and 15 supported upon legs.

The leading feature of the design is the sycamore ornamentation upon the sides a and ends a' of the stove-body A. Clusters, B, of sycamore-leaves appear at the four corners, respectively, of the panel upon the side of the stove, and between the ends of the panel and respectively at the top and bottom thereof are other clusters, B' B', of sycamore-leaves. Upon the panel upon the stove-door a^2 , at its 20 four corners, respectively, are four sycamore-leaves, B ^{2} . Both sides of the stove are similarly ornamented, and upon the rear end of the stove-body is an ornamentation analogous 25

to that appearing upon the stove-door. Upon each of the legs a^3 is a sycamore-leaf, B ^{3} . 30 Aside from the ornamentation described, the stove has a smooth plain finish.

I claim--

1. The design for a heating-stove herein shown and described, the same consisting of the 35 oblong rectangular stove-body having a hearth at one of its ends and legs of the shape shown, said body and legs having superimposed ornamentation representing sycamore-leaves, as set forth. 40

2. In a design for a heating-stove, the design herein shown and described, the same consisting of the panel upon the side of the stove-body, having the superimposed ornamentation grouped thereon representing sycamore-leaves, as shown. 45

3. In a design for a heating-stove, the door rectangular in outline and provided at each corner with ornamentation, consisting of the representation of superimposed sycamore-leaves, 50 as shown and described.

Witness my hand.

HOLMES SMITH.
